(57) **CLAIM**

The ornamental design for a lamp, as shown and described.

DESCRIPTION

FIG. 1 is a front view of a lamp, showing my new design; FIG. 2 is a top and front perspective view thereof; FIG. 3 is a bottom view thereof; FIG. 4 is a top view thereof; FIG. 5 is a right side view thereof; FIG. 6 is a left side view thereof; and, FIG. 7 is a rear view thereof.

The features surrounded by broken lines depict portions of the lamp that form no part of the claimed design.
